UNITED STATES PATENT OFFICE.

LOGEE E. DAVIS, OF HINCKLEY, ILLINOIS.

RIVET BREAKER AND THE LIKE.

Application filed August 2, 1920. Serial No. 400,577.

To all whom it may concern:

Be it known that I, LOGEE E. DAVIS, a citizen of the United States, residing at Hinckley, in the county of De Kalb, in the 5 State of Illinois, have invented certain new and useful Improvements in Rivet Breakers and the like, of which the following is a specification.

The invention has reference to pneumatic 10 tools of the type commonly known as rivet breakers; and the general aim of the invention is to provide a tool of this type which is of a very practical and highly efficient character.

15 In tools of the kind referred to, the valve means for controlling the admission and exhaust of pressure fluid has been in the form of a unitary mechanism located at the hand or rear portion of the tool. This arrangement is objectionable for the reason that the pressure fluid is unable during the forward or driving stroke of the piston to exhaust with sufficient rapidity to prevent a cushioning of the piston, thus reducing the 20 force of its impact upon the cutting implement and hence the efficiency of the tool.

The principal object of my invention is to overcome this difficulty by providing near the forward end of the tool barrel an exhaust port with a valve for controlling the 30 same adapted to be actuated in the operation of the main pressure fluid controlling valve of the tool.

A further and more specific object of the 35 invention is to provide a construction and arrangement of parts which is of a simplified and otherwise practical character avoiding to a maximum degree the use of screws, bolts and other parts which are apt to work 40 loose in the use of the tool to the great danger of the operators.

In the accompanying drawings I have 45 illustrated a preferred embodiment of the invention wherein the valve means at the forward end of the tool is actuated by means of a mechanical connection with the valve means at the rear end of the tool. Obviously, however, the invention is not limited to the precise construction and arrangement herein illustrated and described for I 50 recognize that various changes may be made without departing from the spirit and scope of the invention as expressed in the appended claim.

55 Referring now particularly to the drawings, Figure 1 is a plan view of a tool

embodimenting the features of my invention. Fig. 2 is a fragmentary sectional view on an enlarged scale showing particularly the means for coordinating the valves at the 60 rear and forward ends of the tool. Fig. 3 is a fragmentary transverse sectional view taken substantially in the plane of line 3-3 of Fig. 1. Fig. 4 is a fragmentary sectional view showing in detail the main valve in position to permit of the exhaust of pressure fluid from the rear end of the cylinder upon the return of the piston, the view being taken substantially in the plane 65 of line 4 of Fig. 5. Fig. 5 is a fragmentary 70 vertical sectional view through the tool. Fig. 6 is a transverse sectional view through the forward end of the tool, taken substantially in the plane of line 6-6 of Figs. 5 and 8. Figs. 7 and 8 are fragmentary 75 sectional views taken substantially in the plane of line 7 of Fig. 6 and showing the valve means at the forward end of the tool in different operative positions.

The tool comprises generally a barrel or 80 cylinder 10 having a piston 11 operable therein, and at its forward and rear end, respectively, a tool holder 12 and a head 13 embodying the controlling mechanism for 85 the tool.

The cylinder 10 may be of any preferred 90 construction and size. Preferably, however, it is made of a substantial length so that the piston 11 therein may have a long and hence powerful stroke.

The tool holder 12 may also be of any 95 preferred construction. Herein it consists of a sleeve 14 of cast steel or the like suitably secured upon the forward end of the tool cylinder as by being pressed thereon. At its forward end said sleeve is internally threaded as at 15 to receive the threaded end of a nut 16 through which the shank of a tool 17 is arranged to slide. A coiled compression spring 18 is preferably employed to cushion the blow of the piston in the event that the tool is not applied to the work. This spring bears at its forward end upon the inner end of the nut 16.

The head 13 of the tool may also be secured upon the cylinder at the rearward end thereof as by being pressed thereon. This head provides a pair of handles 19 upon opposite sides thereof, by means of which the tool may be manipulated, and also provides a casing for a portion of the valve mechanism of the tool. Thus referring 105 110 115

2

ticularly to Figs. 2 to 5, the head is provided substantially centrally thereof with a transverse bore 20 providing a chamber for receiving a cylindrical valve member 21 which constitutes the main valve of the tool. Said valve member has a shank 22 extending through an opening 23 in the head, at one end of the bore 20, and the shank has removably secured thereto a handle 24. A coiled compression spring 25, bearing between the head and a collar 26 engaging with the pin 24, serves to maintain the valve member 21 in operative position in the head. At the rear end of the head there is provided a longitudinal bore for receiving a threaded nipple 27 to which may be attached a suitable conductor 28 for pressure fluid. Leading from the passage through the nipple 27, substantially centrally of the head and across the valve chamber 20 therein, is a passage 29 opening into the rearward end of the cylinder 10. In the valve member 21 a port 30 is provided which is adapted to register with the interrupted ends of the passageway 29. It will be seen that when the valve member 21 is properly positioned by the handle 24, pressure fluid will be permitted to pass into the rear end of the cylinder to drive the piston forwardly therein.

To permit of the free and substantially unrestricted exhaust of air or pressure-fluid from the forward end of the cylinder, and thus enable the piston to strike an entirely uncushioned blow upon the shank of the tool 17, I provide an exhaust port 31 (Figs. 7 and 8) at the forward end of the tool, said port being formed by suitable registering apertures in the cylinder 10 and the sleeve 14. A valve member 32 is operable in a bore 33 which extends longitudinally through the sleeve 14 and through the port 31, the sleeve being enlarged as at 14^a for this purpose. This valve member is adapted to control the port 31 and is operatively associated with the valve operating mechanism in the head 13 so that when the valve 21 is moved into a position to permit of the flow of pressure-fluid to the rear end of the cylinder, the valve member 32 is simultaneously operated into position to open the exhaust port 31 and permit of the free passage of air to the atmosphere from the forward end of the cylinder. Herein the means for thus coordinating the movements of the valve member 32 with that of the valve member 21 may comprise a mechanical connection consisting of a rod 34 rigid with the valve member 21 and having at its rear end a head 35 (Fig. 2) provided with rack teeth 36. A pinion 37 rigid with the valve member 21 meshes with the rack teeth 36. Preferably a socket 38 is provided in the lower face of the head 13 to receive the pinion 37 which is made of slightly greater diameter than the valve member proper.

Extending longitudinally of the head, to one side thereof and tangentially of the socket 38, there is provided a bore 39 adapted to neatly receive the head 35 and guide it in its longitudinal movements.

To return the piston 11 to the rear or head end of the cylinder for another stroke, pressure-fluid is conducted to the forward end of the cylinder under the control of the operating means in the head 13. For this purpose I provide in the head 13 a passage 40 communicating at one end with the passage through the nipple 27 and thus with the source of pressure-fluid supply, and extending with an interruption by the bore 20, as shown in Figs. 3 and 5, to the bore 39 in the head (Fig. 2), forwardly of the head 35 on the valve-operating rod 34. Between the head 13 and the sleeve 14 extends a tube 41 having its rear end entered into the forward end of the bore 39 and its forward end entering the rear end of the bore 33 in the sleeve 14. The tube 41 is, of course, made of substantially greater diameter than the rod 34 and is also of greater diameter than the valve member 32 (Figs. 7 and 8) to provide a clearance therebetween. The valve member 32 thus does not restrict the passage of pressure-fluid through the tube 41 into the bore 33.

In order to conduct pressure-fluid from the tube 41 to the forward end of the cylinder, and at the same time close communication between the port 31 and the atmosphere, the valve member 32 is cut away to provide a cavity 42 upon its inner side. Said cavity 42 is of such length that the valve member 32 while closing the port 31 to the atmosphere, (Fig. 8) permits of the passage of pressure-fluid by way of said cavity from the tube 41 into the forward end of the cylinder.

For the purpose of controlling the flow of pressure-fluid through the passage 40 to the tube 41, the main valve member 21 is provided with a port 43 arranged substantially at right angles to the port 30 in the valve member and adapted to establish communication between the interrupted end portions of the passageway 40. It will be apparent that when the port 43 of the valve member is moved into position to connect the opposite portions of the passageway 40, that the port 30 in the valve member will be moved into position to cut off the flow of pressure-fluid to the passageway 29.

In order to permit of the exhaust of pressure-fluid from the rear end of the cylinder when the piston 11 is being returned thereto, the valve member 21 is constructed to provide an exhaust passageway communicating with the rear end of the cylinder. Thus the head 13 is provided with a passageway 44 leading from the rear end of the cylinder to the bore 20 and adapted to reg-

ister with a port 45 (Figs. 4 and 5) opening into a chamber 46 provided in one end of the valve member 21 and opening to the atmosphere.

5 For the purpose of facilitating in the operation of the tool, the positioning of the valve member 21 and hence of the valve member 32 at the forward end of the cylinder, the head 13 is provided upon its upper 10 face with a pair of lugs 47 and 48 oppositely disposed and adapted to be engaged by the handle 24 in its movements. When the handle engages with one of the lugs as, for example, the lug 47 (Fig. 5), the valve 15 mechanism is in position to permit of the passage of pressure-fluid through the passage 29 and port 30 into the rear end of the cylinder to drive the piston forwardly therein, and to permit of the exhaust of 20 pressure-fluid through the port 31 from the forward end of the cylinder, the valve member 32 being in the position shown in Fig. 7. On the other hand, when the handle 24 is moved into engagement with the lug 48, 25 as shown in Fig. 1, pressure-fluid is permitted to flow through the passage 40 and port 39 in the valve member into the passageway provided by the tube 41, and thence by way of the cavity 42 and the port 31 into 30 the forward end of the cylinder. In this latter position of the parts also, the passage 44 leading from the rear end of the cylinder is connected with the port 45 and chamber 46 in the valve member, and thus the 35 pressure-fluid in the rear end of the cylinder escapes to the atmosphere.

It will be seen that I have provided a tool of the type indicated which is of a very practical character. A stroke of any desired length may be obtained for the piston; and by reason of the provision of the exhaust port at the forward end of the cylinder the necessity of the air traveling to the rear end of the cylinder for escape to the 45 atmosphere, as is the case in tools of prior

construction, is avoided. Thus the efficiency of the tool in operation is materially increased.

Moreover, the construction and arrangement of the parts is exceedingly simple. The absence of bolts and screws for connecting the parts of the tool together is particularly noteworthy, and because of the peculiar arrangement of the parts, a single port at the forward end of the cylinder provides for the exhaust of pressure-fluid from the cylinder as the piston is driven forwardly, as well as for the introduction of pressure-fluid into the cylinder to return the piston.

60 I claim as my invention:

A fluid-pressure-actuated tool comprising, in combination, a tubular piston chamber, a piston therein, a valved head at one end of said chamber having therein admission and 65 exhaust ports, a rotary valve member therein to control said ports, a tubular conduit connected at one end to the pressure fluid supply, the piston chamber having a port in the other end passing through said conduit transversely thereof to the atmosphere, a plunger valve in the conduit at its other end movable away from the port to close the conduit and to open the port to the atmosphere and movable toward the port to close 70 the port to the atmosphere simultaneously admitting pressure fluid from the conduit to the piston chamber, a plunger head in the conduit at the first end thereof, a rod enclosed by the conduit connecting the plunger valve and the plunger head, rack teeth on the plunger head, and a gear segment on the rotary valve member engaging the rack teeth, whereby the admission and exhaust 75 of pressure fluid to both ends of the piston chamber are simultaneously controlled.

80 In testimony whereof, I have hereunto set my hand.

LOGEE E. DAVIS.
